UNITED STATES PATENT OFFICE.

HUGO HEIMANN, OF ST. LOUIS, MISSOURI, ASSIGNOR TO THE HEIMANN-MILLER MANUFACTURING COMPANY, A CORPORATION OF MISSOURI.

CABINET.

No. 896,017.

Specification of Letters Patent.

Patented Aug. 11, 1908.

Application filed March 5, 1908. Serial No. 419,270.

To all whom it may concern:

Be it known that I, HUGO HEIMANN, a citizen of the United States, and a resident of the city of St. Louis and State of Missouri, have invented a new and useful Improvement in Cabinets, of which the following is a specification.

My invention relates to cabinets and has for its principal objects to facilitate the operation of the door and to provide for the safe disposition thereof.

It consists in the construction and arrangement of parts hereinafter described and claimed.

In the accompanying drawings, which form part of this specification, and wherein like symbols refer to like parts wherever they occur, Figure 1 is a front elevation of a cabinet embodying my invention; Fig. 2 is a side elevation thereof with the door open; Fig. 3 is a vertical cross section on the line 3—3 of Fig. 1, showing the door moved back inside of the cabinet; Fig. 4 is a vertical cross-section at right angles to the view of Fig. 3, with the door dismounted from its supporting frame; Fig. 5 is a horizontal section of the cabinet with the door open.

The cabinet is preferably of the so-called "unit type" wherein several units or sections are capable of systematic combination. The frame 1 of the cabinet has at one side thereof horizontal tracks 2, 3. The upper track 2 extends from the rear portion of the cabinet forward and is preferably mounted on the underside of the upper side member 4 of the frame. The lower track 3 extends from the front of the cabinet rearwardly and is preferably mounted on the upper side of a horizontal member 5 of the frame located about midway of the height of the cabinet.

On the lower track rests a roller 6 which is mounted on the side of a vertical or upright post or frame 7. Mounted on said post and extending backwardly at the top thereof is a horizontal member 8, which is connected by an inclined piece or bracket 9 to said post. The post, the horizontal member and the bracket together constitute a frame which is supported upon the lower horizontal track 3 by means of the roller 6. Near the rear of the upper end of the bracket is a second roller 10 which is adapted to engage the upper track when the post is in a vertical position. As the upper and the lower tracks are

parallel, the frame may be slid endwise thereof without affecting the vertical position of the post. In order to prevent the lateral movement of the frame, guide strips 11 are fastened to the top and bottom of the cabinet adjacent to said frame.

The door 12 of the cabinet is hung on said post by means of hinges located near the top and bottom thereof, respectively. Each of said hinges preferably comprises a member 13 fastened flatwise to the post and extending beyond the edge thereof, and a second member 14 secured to the door at a slight distance forward of the rear edge thereof and pivotally connected to the outer end of said first-mentioned member. By this arrangement, the door in its open position is in alignment with the frame; and in its closed position the hinge portion thereof extends laterally beyond the pivot point so as to close the entire opening of the cabinet. Preferably, a molding or facing strip 15 is fixed to the cabinet in front of the supporting frame and a limiting strip or shoulder 16 is provided on the side of the frame on the opposite side of the door opening.

The operation of the device is as follows: Normally the door is closed and the cabinet has the appearance of an ordinary cabinet. The weight of the door rests on the post and through the roller thereon is transmitted to the lower horizontal track. The tendency of the door is to tilt the rear end of the frame upwardly, but this tendency is overcome by the upper roller bearing upwardly against the underside of the upper track. Consequently, the post maintains its vertical position. The door is swung upon its hinge until it is in alignment with the supporting frame and then an inward pressure thereon causes the frame to roll rearwardly until the door is inside of the cabinet. In this position, the door is entirely out of the way of adjacent doors and does not obstruct the space in front of its own cabinet.

To limit the outward movement of the door-carrying frame 7, a block or stop 17 is provided at the bottom near the front of the cabinet and against which the lower end of said frame abuts in its forward position. It is preferable, but not absolutely necessary, to provide an antifriction roller 18 which is arranged so that the door passes thereover when moved back into the cabinet. This

roller is provided to support the free end of the door should the same sag, but, ordinarily, when the parts are properly fitted and adjusted, the door will pass clear of said roller.

5 In order to prevent the roller 10 being tilted away from its track 2 by an upward pull on the door, it is desirable to provide a depending member 19, whose lower end will normally lie a slight distance above the lower 10 track 3. This member is mounted upon the frame 7 at any convenient point, preferably on the bracket 9, and constitutes a means for limiting the downward tilting movement of the frame. In order to maintain the 15 proper relative positions and distances of the upper and lower tracks 2, 3, any suitable means for adjusting said tracks may be employed, and I consider it unnecessary to describe any specific means.

20 What I claim is:

1. A cabinet comprising horizontal tracks mounted at one side thereof near the top and middle thereof respectively, a roller frame having a rearwardly projecting member at 25 the top thereof, and a door pivotally mounted on the front part of said frame, said frame being hung near its front on the lower track and having a roller on the rear part of said rearwardly extending member arranged to 30 bear upwardly against the underside of the upper track.

2. A cabinet comprising horizontal tracks mounted at one side thereof near the top and middle thereof respectively, a frame having 35 a rearwardly projecting member at the top thereof, a door pivotally mounted on the front part of said frame, and guides for said frame mounted on the top and bottom portions of the cabinet, said frame being supported on the lower track and having a roller 40 on its rearwardly extending member ar-

ranged to bear upwardly against the underside of said upper track.

3. A cabinet having an upper and a lower horizontal track at the side thereof, a frame 45 having a rearwardly extending member at the top thereof, a door hinged to said frame and having its pivot point inwardly from the margin of said door, and a facing strip at the front edge of the cabinet, said frame having 50 a roller resting on the lower track and having a roller on its rearwardly extending member arranged to bear upwardly against the upper side of said upper track.

4. A cabinet comprising horizontal tracks 55 near the top and middle thereof respectively, a roller frame hung on the lower track and having a roller on its upper rear portion arranged to bear upwardly against the underside of the upper track, and a member pivotally mounted on the front of said frame, said frame comprising a vertical post, a horizontal top member and an inclined member arranged to brace said horizontal member.

5. A cabinet comprising horizontal tracks 65 mounted near the top and middle thereof, and a roller frame hung on the lower track, said frame comprising a vertical member, a horizontal member extending rearwardly at the top thereof and a bracket, said horizontal member having a roller near the rear thereof adapted to bear upwardly against the upper track, and the vertical member having a member located slightly above the lower track rearwardly from the roller thereon. 70 75

Signed at St. Louis, Missouri, this 11th day of February, 1907, in the presence of two subscribing witnesses.

HUGO HEIMANN.
